INTERMEDIATE HALF BEARING FOR ROTARY MECHANISMS

Ferdinand P. Sollinger, Wayne, N.J., assignor to Curtiss-Wright Corporation, a corporation of Delaware
Filed Sept. 16, 1960, Ser. No. 56,369
10 Claims. (Cl. 123—8)

The present invention relates to bearing means for rotary mechanisms and more particularly to an intermediate bearing for use with rotary mechanisms comprising two units which are arranged in tandem relationship and having a common one-piece shaft.

Although this invention is applicable to and useful with almost any type of a multi-unit rotary mechanism comprising two units having a common one-piece shaft which presents an intermediate shaft bearing requirement such as combustion engines, fluid motors, fluid pumps, compressors, and the like, it is particularly useful in rotating combustion engines. To simplify and clarify the explanation of the invention, the description which follows will, for the most part, be restricted to the use of the invention in a rotating combustion engine. It will be apparent from the description, however, that with slight modifications which would be obvious to a person skilled in the art, the invention is equally applicable to other types of rotary mechanisms.

The present invention is particularly useful in rotary mechanisms of the type which comprise an outer body having an axis, axially-spaced end walls, and a peripheral wall interconnecting the end walls. In such rotary mechanism the inner surfaces of the peripheral wall and end walls form a cavity, and the mechanism also includes an inner body or rotor which is mounted within the cavity between its end walls.

The axis of the inner body or rotor is eccentric from and parallel to the axis of the cavity of the outer body, and the rotor has axially-spaced end faces disposed adjacent to the end walls of the outer body, and a plurality of circumferentially-spaced apex portions. The rotor is rotatable relative to the outer body, and its apex portions substantially continuously engage the inner surface of the outer body to form a plurality of working chambers which vary in volume during engine operation, as a result of relative rotation between the rotor and outer body.

The inner surface of the peripheral wall of the outer body has a multi-lobed profile which is preferably of an epitrochoid and the number of lobes of this epitrochoid is one less than the number of apex portions of the inner body or rotor.

By suitable arrangement of ports, such rotary mechanisms may be used as fluid motors, compressors, fluid pumps, or internal combustion engines. The invention is of particular importance when employed with a rotary mechanism which is designed for use as a rotating combustion engine, and accordingly, will be described in combination with such an engine. As the description proceeds, however, it will be apparent that the invention is not limited to this specific application.

When the rotary mechanism is designed for use as a rotating combustion engine, such engines also include an intake passage means for administering a fuel-air mixture to the variable volume working chambers, an exhaust passage means communicating with the working chambers, and suitable ignition means so that during engine operation the working chambers of the engine undergo a cycle of operation which includes the four phases of intake, compression, expansion, and exhaust. This cycle of operation is achieved as a result of the relative rotation of the inner body or rotor and outer body and for this purpose both the inner body or rotor and outer body

2

may rotate at different speeds, but preferably the inner body or rotor rotates while the outer body is stationary.

For efficient operation of the engine, its working chambers should be sealed, and therefore an effective seal is provided between each rotor apex portion and the inner surface of the peripheral wall of the outer body, as well as between the end faces of the rotor and the inner surfaces of the end walls of the outer body.

Between the apex portions of its outer surface the rotor has a contour which permits its rotation relative to the outer body free of mechanical interference with the multi-lobed inner surface of the outer body. The maximum profile which the outer surface of the rotor can have between its apex portions and still be free to rotate without interference is known as the "inner envelope" of the multi-lobed inner surface, and the profile of the rotor which is illustrated in the accompanying drawings approximates this "inner envelope."

For purposes of illustration, the following description will be related to the present preferred embodiment of the engine in which the inner surface of the outer body defines a two-lobed epitrochoid, and in which the rotor or inner body has three apex portions and is generally triangular in cross section but has curved or arcuate sides.

It is not intended that the invention be limited, however, to the form in which the inner surface of the outer body approximates a two-lobed epitrochoid and the inner body or rotor has only three apex portions. In other embodiments of the invention the inner surface of the outer body may have a different plural number of lobes with a rotor having one more apex portions than the inner surface of the outer body has lobes.

The output of conventional piston and cylinder reciprocating type internal combustion engines can be increased by adding additional piston and cylinder combinations. Similarly, the output of rotary combustion engines of the type described can be increased by adding rotor and housing units. This may be done, for example, by coupling the shafts of a plurality of rotor and housing units together. Such a split shaft construction however, is structurally weak compared to a single-piece shaft.

In order that a single-piece shaft could be used in a multi-unit rotary combustion engine, it has been proposed that no bearing be used for the shaft intermediate the eccentric portions of the shaft. This was found to be unsatisfactory since the high level of gas forces developed in such mechanisms resulted in deflection and bending of the shaft having obvious deleterious effects on the shaft. When deflected, the shaft also tended to be tilted or cocked in the end bearings which put an undesirable stress and strain on the end bearing resulting in poor shaft support and undue wear and eventual destruction of the end bearings.

It has also been proposed that a single-piece shaft be used which has a thickened cross section intermediate the eccentric portions of the shaft. Although this will reduce somewhat the bending and deflection of the shaft, deflection which does occur subjects the end bearings to an undesirable amount of stress resulting in poor bearing support of the shaft and eventual failure of the end bearings.

In the case of a one-piece shaft for a multi-unit rotary engine, a sectional or split bearing which included some means of removably engaging the sections of the bearing has been proposed. When using such sectional bearings intermediate the eccentric portions of the shaft of the multi-unit rotary engine, it was found necessary to construct the intermediate housing of a plurality of parts, generally two parts.

A two-piece intermediate housing was necessary in order to assemble the sectional bearing within the intermediate wall since to provide a bore in a unitary housing

of sufficient diameter to permit assembly of the sectional bearing, would result in a decrease of bearing contact between the rotor and outer body end walls. The use of such an enlarged bore would result in locating the oil seal a substantial distance from the shaft, whereas in order to reduce the centrifugal forces on the oil seal it is generally recognized that the oil seal should be located adjacent the inner edge of the rotor and as close as possible to the shaft.

A two-piece intermediate housing wall required additional cooling passages, one for each portion of the housing intermediate wall, as well as bolt means for joining the intermediate housing wall parts. This results in a multi-unit construction having a relatively long length and a unit having an increased number of parts.

In accordance with the present invention, a semi-circular intermediate shaft bearing is provided which leads to new, useful and unexpected results.

In accordance with the present invention the lobes on the outer body epitrochoid, the intake ports, the exhaust ports and the combustion phases for two rotary engines are located so that when viewed along the axis of these units, they are substantially aligned behind one another. The expanding gas force resulting from the combustion phase, will for each rotary combustion unit be in the same direction on the rotor. The present invention contemplates the use of a semi-circular bearing for supporting the portion of the shaft intermediate the eccentrics against that gas force.

The above alignment of elements and combustion phases in combination with the semi-circular bearing permits the use of a single-piece relatively small diameter shaft which will resist bending and deflection substantially as well as when the sectional type bearing discussed previously is used. The present invention has, however, an additional advantage that the sectional bearing does not, in that the present semi-circular bearing can be used with a unitary intermediate housing, thereby reducing the overall length and complexity of the multi-unit combination. The semi-circular bearing of the present invention can be easily assembled within the outer body intermediate walls and requires a bore in the housing which is only slightly greater than the diameter of the eccentric portion on the shaft. Thus, maximum permissible bearing contact between the rotor and the end walls of the outer body is maintained.

The semi-circular bearing of the present invention provides a shaft which will resist gas deflection better than a single-piece shaft having a thickened portion intermediate its eccentrics and will, therefore, prevent the end bearings from being subjected to undesirable wear and tear.

In view of the foregoing, it is an object of this invention to provide a bearing for a shaft intermediate its eccentric portions which can be easily, expeditiously and efficiently assembled.

It is a further object of this invention to provide an intermediate bearing for supporting a shaft intermediate its eccentric portions have novel means for preventing axial and rotative movement of the bearing with respect to the outer member.

It is a still further object of this invention to provide a bearing for supporting a shaft intermediate its eccentric portions which, when assembled within an outer member, is keyed to the outer member to prevent axial movement of the bearing with respect to the outer member.

It is another object of this invention to provide a semi-circular bearing for supporting a shaft intermediate its eccentric portions having a semi-circular diameter such that it can be assembled with the associated outer member having a bore only slightly greater than the diameter of the eccentric portions on the shaft.

It is yet another object of the present invention to provide a bearing for supporting a shaft intermediate its eccentric portions which will efficiently and effectively

support its associated shaft from the stresses induced by the gas pressures developed during the combustion phase.

Another object of this invention is to provide a bearing for supporting a shaft intermediate its eccentric portions wherein the shaft is associated with a plurality of rotary combustion units having combustion phases located with respect to the bearing such that a semi-circular bearing may be used.

Still another object of this invention is to provide a bearing for use with two rotary combustion phases located with respect to the outer body in a manner whereby a semi-circular bearing may be mounted in the outer member in a position opposite to the combustion phases for supporting a shaft intermediate its eccentric portions from the gases developed during combustion:

Still further object of the present invention is to provide a plurality of rotary combustion units arranged in tandem wherein each unit has its combustion phase located in a position relative to its outer member so that a bearing having a substantially semi-circular contour, having novel means for preventing axial and rotative movement, is mounted in the outer body in a position opposite to the combustion phases for supporting a shaft from the combustion gas force to which it is subjected.

Additional objects and advantages of the invention will be set forth in part in the description which follows and in part will be obvious from the description or may be learned by practice of the invention, the objects and advantages being realized and attained by means of the instrumentalities and combinations particularly pointed out in the appended claims.

The invention consists in the novel parts, constructions and improvements shown and described.

In accordance with this invention, a single-piece shaft having eccentric portions spaced along its length is provided with a semi-circular bearing means for supporting the shaft intermediate the eccentric portions.

Briefly described, the bearing means is used with a plurality of rotary engine units having a common one-piece power shaft and having their combustion phases in the same position relative to their outer bodies, the bearing means having a substantially semi-circular profile removably engaged with the intermediate wall of the outer body in a position opposite from the location of the combustion phases for supporting the single-piece power shaft intermediate eccentric portions on the shaft.

The accompanying drawings, which are incorporated in and constitute a part of this specification, illustrate one embodiment of the invention and, together with the description, serve to explain the principles of the invention.

Of the drawings:

FIGURE 1 is a sectional view taken along line 1—1 of FIGURE 2 showing two rotary mechanisms in tandem relationship.

FIGURE 2 is a section view taken along line 2—2 of FIGURE 1.

FIGURE 3 is a sectional view taken along line 3—3 of FIGURE 1.

FIGURE 4 is a sectional view taken along line 4—4 of FIGURE 3 showing the intake port construction.

FIGURE 5 is a side view of the intermediate bearing.

FIGURE 6 is an end view of the intermediate bearing.

FIGURE 7 is a schematic view showing the intermediate bearing being assembled within the outer body.

It is to be understood that both the foregoing general description and the following detailed description are exemplary and explanatory but are not restrictive of the invention.

Reference will now be made in detail to the present preferred embodiment of the invention, an example of which is illustrated in the accompanying drawings.

In accordance with the present invention, two rotary combustion engines are provided which are in side-by-side or tandem relationship. As embodied and shown in FIGURES 1-3, the present preferred embodiment includes a

rotary combustion engine unit comprising in tandem arrangement a pair of rotating combustion engines A and B, FIGURES 1-2, arranged and disposed coaxially of one another.

In order to simplify the drawings, portions of the engines A and B not essential to an understanding of the invention have been omitted and corresponding parts in engines A and B are designated by the same reference numerals, the reference numerals for engine B being primed. Accordingly, it will be understood that the section taken along 2-2 of FIGURE 1 and shown in FIGURE 2 would serve equally well for engine B.

Both of the rotating combustion engines are of similar construction, and each comprises a generally triangular rotor 10, 10' having arcuate sides which are eccentrically supported for rotation within an outer body 12, 12'. Although in the present preferred embodiment the outer body 12, 12' is fixed or stationary, the engine is not limited to this preferred embodiment, e.g., either body may be stationary or both bodies may rotate, one relative to the other.

As shown in FIGURES 1 and 2 and as here preferably embodied, the outer body 12, 12' comprises a peripheral wall 18, 18' the inner surface of which is substantially an epitrochoid in geometric shape, and includes two arched lobe-defining portions or lobes, the two epitrochoids being coaxial with their lobes aligned. In other words, the lobes of one epitrochoid are directly behind the lobes of the other epitrochoid when viewed in a direction parallel to the axis. The outer body also comprises a pair of axially-spaced end walls, 22, 22' and 24, 24' which are disposed on opposite sides of the peripheral wall 18, 18'. The two end walls 24, 24' have a one-piece construction forming an intermediate housing wall member.

The end walls 22, 22' and 24, 24' support a common shaft 26, the geometric center of which is coincident with the axis 16 of the outer body 12, 12'. This common shaft 26 is supported for rotation by the end walls 22, 22' on end bearings 28, 28'. A pair of eccentrics 30, 31' are rigidly attached to the common shaft 26, and the rotor 10, 10' is supported for rotation or rotatably mounted upon the eccentric 30, 31' by suitable anti-friction bearings 32, 32'. The axis 14, 14' of the engine eccentrics is displaced a distance *e* from the axis 16.

As shown in FIGURE 1, an internally-toothed or ring gear 34, 34' is attached to the bearing 32, 32' which in turn is rigidly attached to the rotor 10, 10' to prevent relative rotation of the gear and rotor. The ring gear 34, 34' is in mesh with an externally-toothed or pinion gear 36, 36' which is rigidly attached to the stationary end wall 22, 22' of the outer body 12, 12'.

From this construction it may be observed that the gearing 34, 34' and 36, 36' does not drive or impart torque to the crankshaft but merely serves to index or register the position of the rotor with respect to the outer body and removes the positioning load which would otherwise be placed upon the apex portions of the rotor 10, 10'.

As shown most clearly in FIGURE 2, the rotor 10, 10' includes three apex portions 38, 38' which carry radially movable sealing members 40, 40'. The sealing members 40, 40' are in substantially continuous sliding, gas-sealing contact with the inner surface 20, 20' of the outer body 12, 12' as the rotor 10, 10' rotates within and relative to the outer body 12, 12'. The end walls of the rotor have mounted therein gas-sealing means 76, 76' so that by means of the rotation of the rotor 10, 10' relative to the outer body 12, 12' three variable volume working chambers 42, 42' are formed between the peripheral working faces 44, 44' of the rotor 10, 10' and the inner surface 20, 20' of the outer body 12, 12'. As embodied in FIGURE 2, the rotation of the rotor relative to the outer body is counter-clockwise and is so indicated by an arrow.

A spark plug 46, 46' is mounted in the peripheral wall 18, 18' of the outer body 12, 12', and at the appropriate time in the engine cycle, the spark plug 46, 46' provides

ignition for a compressed combustible mixture which on expansion, drives the rotor in the direction of the arrow.

As shown most clearly in FIGURES 1, 3 and 4 end wall 24, 24' is provided with an intake port or passage 48, 48' and the peripheral wall 18, 18' is provided with an exhaust port 50, 50'. As the rotor rotates, a fresh charge is drawn into the working chambers 42, 42' through the intake ports 48, 48'. This charge is then successively compressed, ignited, expanded, and finally exhausted through the exhaust port 50, 50'.

With reference to FIGURE 4 it can be seen that the adjacent end walls 24, 24' each have an intake port 48, 48' wherein these ports merge with a common inlet 47 at the outer periphery of the housing members. This arrangement provides a very compact arrangement for supplying a fresh charge to the working chambers of the engine.

All four successive phases of the engine cycle: intake, compression, expansion, and exhaust, take place within each one of the variable volume working chambers 42, 42' each time the rotor 10, 10' completes one revolution within the outer body, and for each revolution of the rotor, the engine completes a cycle.

The working faces 44, 44' of the rotor 10, 10' are provided with cut-out portions or channels 52, 52' which permit combustion gases to pass freely from one lobe of the epitrochoidal inner surface 20, 20' to the other lobe, when the rotor is at or near the top dead center compression position. Also, the compression ratio of the engine may be controlled by adjusting the volume of the channels 52, 52'.

Since the gear ratio between the ring gear 34, 34' and the pinion gear 36, 36' is 3:2, each time the rotor 10, 10' completes one revolution about its own axis 14, 14' the shaft 26 rotates three times about its axis 16.

In accordance with this invention certain elements of the rotary combustion engines are aligned or arranged with respect to one another such that a semi-circular bearing can be used to provide new, useful and beneficial results.

In the preferred embodiment of the invention which is illustrated in the drawings, eccentrics 30, 30' and therefore the rotors 10, 10' are rotatively displaced 180° with respect to one another. This is most clearly illustrated in FIGURE 1 and FIGURE 2. When the eccentrics are rotatively displaced 180° as illustrated, the loads on the intermediate portions of the shaft resulting from the centrifugal forces on the eccentrics 30, 30', is at a minimum. On the other hand, the lobes on the inner surface 20, 20', the intake port 48, 48', the exhaust port 50, 50' and the ignition means or spark plug 46, 46' are arranged so that when observed on a line parallel to the axis they are located one behind the other.

It will be recognized by those skilled in the art, however, that substantial alignment is all that is necessary. For example, the ignition means 46, 46' could be located on opposite sides of the adjacent junction point of the two lobes of their respective engine units without changing the relative position of the combustion phases for each engine. This arrangement of elements is such that although rotors are displaced 180° angularly with respect to one another and, therefore, the working chambers are also angularly displaced 180° with respect to one another, that the working phases of the units will always occur in working chambers having the same location with respect to the housing.

In other words, it is obvious that the combustion phase will always occur in the lower portion of the housing adjacent the ignition means 46, 46' for each engine. Thus, the maximum gas pressure on the rotor, i.e., created by the combustion phase, will, for each engine unit, be in a direction which is upwardly or generally toward the intake and exhaust ports. The shaft will, as a result of these conditions, be subjected to a gas force

in the same direction from each of the rotors 10, 10' of the two engine units.

The intermediate bearing means, as herein embodied, is most clearly illustrated in FIGURES 1 and 3-6. The bearing means 56, in accordance with this invention, is mounted for supporting the shaft 26 intermediate the eccentrics 30, 30'. It will be appreciated by those skilled in the art that where a one-piece shaft is used, it would not be possible to locate a single-piece annular bearing in this position in a rotary mechanism of the type 10 described.

The half-bearing 56, as embodied, has substantially a semi-circular profile, as can be seen in FIGURE 3. The bearing surface 58 of the bearing is in engagement with the shaft 26, on the side of the shaft which is opposite to the ignition means 46, 46'. Means are provided in accordance with this invention for removably attaching the bearing to the housing.

As shown in FIGURES 1 and 4, an intermediate housing member is formed from side walls 24, 24' which are joined by an annular flange or portion 60 which has a bore therein forming bearing engaging surface 62 for continuous engagement with the housing engaging surface 64 of the bearing. This bore has virtually the identical radius of curvature as the housing engaging surface 64 on the half-bearing 56. The half-bearing is also provided with a tapered key means 66 for engagement with the key-way 68 in the flange 60 of the housing. It can be observed in FIGURES 3 and 7 that the key 66 has the same radius of curvature as the outer surface 64 of the half-bearing but that the center 59 of the radius of key 66 is displaced toward the half-bearing from the center 61 of the bearing such that the key 66 is, in effect, tapered with respect to the housing engagement surface 64. The key-way 68 has a larger radius of curvature than the key 66.

As shown in FIGURE 5, the key portion 66 is substantially flush with the external surface 64 of the bearing at its end portions and has its maximum radial depth at the center line 67 of the bearing. This construction has been provided so that the half-bearing can be easily assembled to the housing without the necessity for an excessively large opening in the end wall 24, 24' and hence without sacrificing a substantial amount of bearing surface between the end walls of the outer body and the rotor.

The preferred manner of assembling the semi-circular bearing to the housing or outer member is shown in FIGURE 7. Although the bearing 56 has been described as semi-circular or a half-bearing as illustrated it is an arcuate segment which is somewhat less than a semi-circle. Accordingly, the expressions "semi-circular" and "half bearing" in the claims are intended to be construed sufficiently broad to include a bearing which is somewhat less than a semi-circle. The half-bearing 56 is assembled by first placing the shaft 26 in the rotative position within the intermediate housing wall 24, 24', as shown in FIGURE 7, and then laterally displacing the shaft, downwardly, as viewed in FIGURE 7, to the maximum extent permitted by the bore 62 in the housing wall. The half-bearing 56 can then be moved axially over the shaft into position within the housing intermediate wall, as illustrated in FIGURE 7, with the key 66 in alignment with the key-way 68. The semi-circular bearing need then only be moved a slight radial distance outward to engage the key 66 in the key-way 68.

As illustrated in FIGURE 7, the fact that the key 66 and bearing engaging surfaces 62 have the same radius permits the bearing 56 to be assembled within the housing wherein the housing has a bore only slightly larger than the diameter of the eccentric. By this relationship of curvatures, hereinbefore discussed, it is possible to provide a bore in the housing which permits maximum bearing contact between the end walls of the rotor 10, 10' and the intermediate end walls 24, 24' of the outer mem-

ber. This arrangement also permits the oil seal 75, 75' to be located as close as possible to the shaft 26 thereby reducing the centrifugal forces on the oil seals.

After the intermediate bearing 56 has been assembled within the housing, the rotor 10, 10' with its bearing 32, 32' may be assembled on the eccentrics 30, 30' and the peripheral walls 18, 18' and the end walls 22, 22' of the outer body placed in position. Finally, the end bearings 28, 28' can be bolted or otherwise secured to the end walls 22, 22' of the outer body.

The key and key-way combination 66, 68 will, of course, prevent axial movement and/or tilting of the bearing within the housing and insures that the bearing will remain in continuous bearing contact with the shaft. It will be appreciated by those skilled in the art that the invention is not limited to a construction where the key is on the bearing and the key-way in the housing and that these elements may be reversed without departing from the principles of this invention.

In order to maintain the bearing in assembled relationship with the housing during subsequent assembly steps and for preventing rotation of the bearing with respect to the shaft, means are provided for locking the half-bearing to the housing. As embodied herein, this means comprises a screw means 70 cooperating with aperture 72 in the housing and threaded aperture 74 in the bearing. The screw means will, in an obvious manner, maintain the bearing and the housing in tight locking engagement.

It will be obvious that other and equivalent means may be used in lieu of the key and key-way means and that other means equivalent to the screw means may be used in the practice of this invention.

Accordingly, the invention in its broader aspects is not limited to the specific mechanisms shown and described, but also includes within the scope of the accompanying claims any departures made from such mechanisms which do not sacrifice its chief advantages.

What I claim is:

1. A rotary combustion engine comprising a multi-part housing having first and second axially-spaced end walls, an intermediate wall having a one-piece construction, a first peripheral wall secured to and disposed between the outer portions of said first and said intermediate wall to form a first cavity between and a second peripheral wall secured to and disposed between the outer portions of said second and said intermediate wall to form a second cavity; a one-piece shaft co-axial with said cavities and having a pair of eccentric portions, one for each of said cavities; first and second rotor members extending within said first and second cavities respectively with each rotor member being journaled on the associated shaft eccentric, each rotor member having a plurality of circumferentially-spaced apex portions for engagement with the inner surface of its associated peripheral wall to divide the portions of its associated cavity between said rotor member and inner surface into a plurality of working chambers which vary in volume upon rotation of the rotor member relative to the housing, said housing having intake and exhaust ports communicating with the working chambers of said first cavity and having intake and exhaust ports communicating with the working chambers of the second cavity with corresponding ports of said first and second cavities being disposed substantially one behind the other when viewed in a direction parallel to said axis; and a semi-cylindrical half bearing carried by said intermediate wall for bearing engagement with the portion of the shaft between said shaft eccentrics and on the side of said shaft for supporting said shaft portion against deflection by the forces transmitted against the shaft by the rotor resulting from the high gas pressures within each working chamber following combustion therein.
2. A rotary combustion engine comprising a multi-part housing having first and second axially-spaced end walls, an intermediate wall, a first peripheral wall secured to and disposed between the outer portions of said

first and said intermediate wall to form a first cavity therebetween and a second peripheral wall secured to and disposed between the outer portions of said second and said intermediate wall to form a second cavity therebetween co-axial with said first cavity; a one-piece shaft co-axial with said cavities and having a pair of eccentric portions, one for each of said cavities; first and second rotor members extending within said first and second cavities respectively with each rotor member being journaled on the associated shaft eccentric, each rotor member having a plurality of circumferentially-spaced apex portions for engagement with the inner surface of its associated peripheral wall to divide the portions of its associated cavity between said rotor member and inner surface into a plurality of working chambers which vary in volume upon rotation of the rotor member relative to the housing, said housing having intake and exhaust ports communicating with the working chambers of said first cavity and having intake and exhaust ports communicating with the working chambers of the second cavity with corresponding ports of said first and second cavities being disposed substantially one behind the other when viewed in a direction parallel to said axis; and a semi-cylindrical half bearing carried by said intermediate wall for bearing engagement with the portion of the shaft between said shaft eccentrics and on the side of said shaft for supporting said shaft portion against deflection by the forces transmitted against the shaft by the rotor resulting from the high gas pressures within each working chamber followed combustion therein, and said semi-cylindrical bearing and said intermediate housing having a key and keyway means cooperating therewith for preventing axial movement of said semi-cylindrical bearing means with respect to said intermediate wall.

3. A rotary combustion engine comprising a multi-part housing having first and second axially-spaced end walls, an intermediate wall, a first peripheral wall secured to and disposed between the outer portions of said first and said intermediate wall to form a first cavity therebetween and a second peripheral wall secured to and disposed between the outer portions of said second and said intermediate wall to form a second cavity therebetween co-axial with said first cavity; a one-piece shaft co-axial with said cavities and having a pair of eccentric portions, one for each of said cavities; first and second rotor members extending within said first and second cavities respectively with each rotor member being journaled on the associated shaft eccentric, each rotor member having a plurality of circumferentially-spaced apex portions for engagement with the inner surface of its associated peripheral wall to divide the portions of its associated cavity between said rotor member and inner surface into a plurality of working chambers which vary in volume upon rotation of the rotor member relative to the housing, said housing having intake and exhaust ports communicating with the working chambers of said first cavity and having intake and exhaust ports communicating with the working chambers of the second cavity with corresponding ports of said first and second cavities being disposed substantially one behind the other when viewed in a direction parallel to said axis; and a semi-cylindrical half bearing carried by said intermediate wall for bearing engagement with the portion of the shaft between said shaft eccentrics and on the side of said shaft for supporting said shaft portion against deflection by the forces transmitted against the shaft by the rotor resulting from the high gas pressures within each working chamber following combustion therein, said semi-cylindrical bearing having an intermediate wall engaging surface and a key tapered with respect to said engaging surface and extending radially from said engaging surface for preventing axial movement of said semi-cylindrical bearing.

4. A rotary combustion engine as defined in claim 3 wherein the intermediate wall has a bearing engaging surface having the same radius of curvature as the key.

5. A rotary combustion engine as defined in claim 4 including means for preventing rotative movement of said semi-cylindrical bearing with respect to said intermediate wall.
- 5 6. A rotary mechanism comprising a plurality of units each unit having a hollow outer body on a common axis, axially-spaced end walls, and a peripheral wall interconnecting the end walls; each unit also having an inner body mounted within the outer body for rotation relative to the outer body on an axis eccentric, spaced from and parallel to the axis of the outer body; each inner body having end faces disposed adjacent to the end wall and a plurality of circumferentially-spaced apex portions in sealing engagement with the inner surface of the peripheral wall to form a plurality of working chambers between the inner body and the peripheral wall which vary in volume upon relative rotation of the inner body within the outer body, the inner bodies for each unit being mounted on angularly displaced eccentric portions of a 10 common single-piece shaft, means for forming combustion phases for each unit in the same position relative to their outer bodies so that the combustion gases will be directed against each inner body in the same direction and semi-cylindrical bearing means carried by said outer bodies for supporting said single-piece shaft intermediate said eccentric portions from deflection by the forces transmitted against the shaft resulting from the combustion gases.
- 20 7. A bearing for supporting the intermediate portion 30 of a shaft in rotary mechanisms having a housing and a shaft with eccentric portions thereon mounted within the housing comprising: a substantially semi-circular profiled bearing surface and a substantially semi-circular profiled housing engaging surface, said housing engaging 35 surface including a key means having the same radius of curvature as said housing engaging surface, said key extending from one end to the other of said bearing and having its maximum radial depth disposed intermediate the ends of the bearing.
- 40 8. A rotary combustion engine comprising a multi-part housing having first and second axially-spaced end walls, an intermediate wall having a one-piece construction and an axial bore therein, a first peripheral wall secured to and disposed between the outer portions of said first and 45 said intermediate wall to form a first cavity therebetween and a second peripheral wall secured to and disposed between the outer portions of said second and said intermediate wall to form a second cavity therebetween co-axial with said first cavity; a one-piece shaft co-axial with said cavities and having a pair of eccentric portions, one for each of said cavities; first and second rotor members extending within said first and second cavities respectively with each rotor member being journaled on the associated shaft eccentric, said rotor members cooperating 55 with their walls of the housing cavities to form a plurality of working chambers therebetween which vary in volume upon relative rotation of said rotor members and housing; means providing for combustion in said working chambers such that the maximum combustion gas forces 60 on said rotor member are in substantially the same direction relative to the axis of said shaft; and a semi-circular bearing carried by said intermediate wall for bearing engagement with the portion of the shaft between said shaft eccentrics and on the side of said shaft for supporting said shaft portion against said combustion gas forces.
- 65 9. In combination with a rotary mechanism having a housing with a bore and a shaft with eccentric portions spaced axially of said shaft, a bearing comprising: a semi-circular housing engaging surface, said housing engaging surface including key means, said key means, said housing engaging surface and said bore having virtually identical radii of curvature said radii of curvature being the minimum permissible radii for passing said eccentrics through said bore.
- 70 10. A rotary combustion engine comprising a multi-

part housing having first and second axially-spaced end walls, an intermediate wall having an axial bore therein, a first peripheral wall secured to and disposed between the outer portions of said first and said intermediate wall to form a first cavity therebetween and a second peripheral wall secured to and disposed between the outer portions of said second and said intermediate wall to form a second cavity therebetween co-axial with said first cavity; a shaft co-axial with said cavities and having a pair of eccentric portions, one for each of said cavities; first and second rotor members extending within said first and second cavities respectively with each rotor member being journaled on the associated shaft eccentric, each rotor member having a plurality of circumferentially-spaced apex portions for engagement with the inner surface of its associated peripheral wall to divide the portions of its associated cavity between said rotor member and inner surface into a plurality of working chambers which vary in volume upon rotation of the rotor member

relative to the housing, said housing having intake and exhaust ports communicating with the working chambers of said first cavity and having intake and exhaust ports communicating with the working chamber of the second cavity with corresponding ports of said first and second cavities being disposed substantially one behind the other when viewed in a direction parallel to said axis; and an arcuate bearing segment carried by said intermediate wall for bearing engagement with the portion of the shaft between said shaft eccentric and on the side of said shaft for supporting said shaft portion against deflection by the forces transmitted against the shaft by the rotor members resulting from the high gas pressures within each working chamber following combustion therein.
